Application May 31, 1940, Serial No. 332,111

1 Claim. (Cl. 179—171)

This invention relates to amplifiers and, more particularly, to vacuum tube amplifiers suitable for the amplification of voltage or current changes in direct as well as alternating current circuits.

The use of vacuum tubes for the amplification of steady or slowly varying potentials has been very limited due to the difficulties in the design of circuits for this purpose. The primary difficulty is found in the coupling of amplifier stages between the output of one tube and the input of a succeeding tube. For this reason, amplifiers of signals which have slowly changing components have been limited largely to single vacuum tubes used in connection with a sensitive meter. Since operating voltages of an amplifier include the application of positive potentials between cathode and anode, whereas the potentials between cathode and control electrode extend into a negative polarity range, the anode of one tube cannot be connected directly in the manner conductive to direct current to the control element of a succeeding tube if the cathodes of all the tubes are to be maintained at a uniform potential. A direct connection in such circumstances would apply the relatively high positive potential of the anode to the negatively biased control grid of the succeeding tube with detrimental results.

In order to effect coupling between amplifier stages, it is the practice to insert a condenser in the connection between anode and grid which isolates the respective direct current potentials applied to the tube elements. The disadvantage of such arrangements is found in the reactance variation of the coupling capacity with frequency of the signal voltage to be amplified. Furthermore, an amplifier with capacitive coupling is limited to alternating current signal voltages. Various circuits have been devised in the past for amplifiers to operate on direct current or slowly varying input potentials. In these the coupling capacity is usually replaced by batteries or the stages have to be cascaded in such manner that the cathodes of the tubes are at different potentials with respect to each other. While such arrangements permit direct coupling of successive stages, the circuits are extremely critical and require a number of isolated power supplies and very high voltages. The large number of circuit components also seriously affect the stability of the entire system.

A particular feature of this invention is the direct conductive connection between output and input elements of cascaded vacuum tube amplifier stages with all the cathodes of the tubes at uniform potential. This permits slowly varying or

constant (direct current) changes of signal input voltages to be amplified, as well as higher frequencies, extending well beyond the audio frequency spectrum.

Another important feature of this invention is the simple circuit arrangement utilizing a minimum number of components for the amplifier which is capable of direct current or alternating current signal amplification.

A further advantage of the amplifier constructed in accordance with this invention is the stability of the circuit with only normal filtering and regulation of the supply voltage which may be derived from a common power supply for all tubes and the adaptability to utilize inverse feedback between stages.

Other features and advantages will be apparent from the following description of the invention, pointed out in particularity in the appended claim, and taken in connection with the accompanying drawings, in which:

Figure 1 shows a schematic circuit arrangement of a simple two stage direct coupled amplifier in accordance with this invention;

Fig. 2 is a modification thereof with insertion of inverse feedback between the first and the last stage.

Fig. 3 shows a complete circuit of a power line operated amplifier of three cascaded stages, whereas

Fig. 4 is the modified circuit of the above with inclusion of inverse feedback.

Identical elements in the various figures of the drawings are identified with similar reference characters.

Referring to the drawings, in Fig. 1 a simple amplifier circuit includes the input terminals across potentiometer 1, the lead 2 from which connects to the grid 3 of amplifying tube 5. The suitable biasing potential for the grid 3 is obtained by means of potentiometer 6 connected between the cathode 7 of tube 5 and the supply conductor 9. The rider 10 of the last-mentioned potentiometer connects to the ground potential terminal of the input circuit including terminal 11 of potentiometer 1. The anode circuit of the tube 5 comprises the anode 12, the load resistance 14 which terminates at the anode potential supply conductor 15. Between the anode 12 and the supply conductor 9 is placed a voltage dividing and coupling network comprising resistors 16, 17 and the variable resistor 18 connected in series. The input to the grid 20 of the succeeding amplifier tube is effected at the junction point of resistors 16 and 17 to which the grid 20 is directly

connected. The cathode 21 of the amplifier tube 19 connects to the common supply conductor 22 which interconnects all cathodes and terminates at the common connection between the anode power supply "B" and the bias power supply C. The current flow which is desirable through the series connected resistors 16, 17 and 18 may be controlled by the variable contact 23 of the resistor 18 which is connected to the most negative portion of the system represented by the supply conductor 9. The anode 25 of the tube 19 connects through a suitable load impedance device, shown here by the relay winding 26 to the highest positive potential side of the system represented by the supply conductor 15. The relay is indicated to have an armature 28 and contacts 29 and 29' for various switching applications as may be desirable, depending upon what utilitarian purpose the amplifier may serve. The two power supplies are merely shown in block diagrams since many different types may be used with equal facility such as batteries, or rectified and filtered alternating current supplies.

In Fig. 2 the amplifier circuit shown is very similar to the one in Fig. 1, the only modification being in the inverse feedback circuit which is particularly advantageous for increased stability of operation. It will be sufficient to describe only the changes necessary for obtaining inverse feedback voltage, the remaining part of the circuit being identical with the one previously described. It is to be noted that the bias voltage for the grid 3 of the first amplifier tube 5 is now obtained not only from the bias potential source C through the adjustment of the rider 10 of the potentiometer 6 but also through the adjustment of the rider 30 of the potentiometer 31 which is in series between cathode 21 and the common supply conductor 22. In this manner, by the adjustment of the rider 30, the voltage appearing across the cathode resistor 31 may be partly or entirely combined in the proper polarity relation with the bias voltage of the bias potential source C. In the output circuit of the tube 19, there is shown by way of example an output transformer 32 taking the place of the relay winding 26 shown in Fig. 1. Relays or indicating instruments in the output circuit may be employed particularly when slowly varying direct current potentials are to be amplified, whereas for alternating current signal amplification, various types of output transformers may be used.

The principle of operation of the system may be understood by referring to Figure 1 and considering the load resistance 14 of amplifying tube 5 in connection with the coupling network comprising resistors 16, 17 and 18. Resistors 17 and 18 may be taken as a single resistance element, namely 17 plus 18 and designated as R_3 , whereas 16 as R_2 and the load resistance 14 as R_1 . By the use of this simplified designation the purely numerical identification used in the drawings will not be confusing in mathematical forms of quantitative expressions. The conductive coupling R_2 and R_3 performs a dual function of which the first one is the original signal transfer from the plate circuit to the grid of the succeeding amplifier tube and the second function is to provide a certain voltage ratio in direct current potentials whereby the grid of the tube to which it is connected should be suitably biased at a potential value more negative than its cathode. In other words, the resistors R_2 and R_3 , determine the proper zero signal potential for

the grid 20, which gives the static condition of the amplifier. Considering this, the cathodes of the tubes may be taken as a reference point for the various static potentials, since all cathodes are at substantially the same potential. Hence, with respect to the cathode 7 the potential of the anode 12 of tube 5 will be of some positive value which may be called E_{p1} and will be approximately one-half of the terminal voltage of the supply B, namely $E_B/2$. The potential difference between the anode 12 and the most negative portion of the system at the junction point of the resistor 18 and the conductor 9, designated as A, will be the effective anode potential plus the potential of the bias source C, that is $E_{p1} + E_c$. If we denote the potential value whereby the grid 20 is more negative than the cathode 21 as E_g , then:

$$20 (1) \quad E_g = \frac{R_3}{R_2 + R_3} (E_{p1} + E_c) - E_c$$

R_3 is so adjusted that the proper grid potential is obtained to locate the operating point of tube 19 near the center of the linear portion of its transfer characteristic and allowed to remain at this adjustment. Now, R_2 and R_3 form a potentiometer between the anode 12 and the point A whose potential is fixed by the supply C. Within the operating range in which the grid 20 draws negligible current (the normal working range), it is apparent that a fraction of any change in the potential of the anode 12 of tube 5 will be impressed on the grid 20, since the voltage relation is determined by

$$35 \quad \frac{R_2}{R_2 + R_3}$$

which, as will be seen, represents the efficiency of coupling.

40 In Equation 1 E_g may be neglected in comparison with the terms on the right side thereof which then breaks down to the approximate expression:

$$45 \quad \text{Efficiency of coupling} = \frac{R_3}{R_2 + R_3} = \frac{E_c}{\frac{E_B}{2} + E_c}$$

wherein R_3 represents the resistors 18+17; R_2 resistor 16; E_c the bias voltage supply and E_B the anode voltage supply of Figure 1.

50 Now, if

$$E_B = \frac{E_c}{2}$$

which can easily be realized in a practical arrangement, then

$$\text{Efficiency} = \frac{E_c}{\frac{E_c}{2} + E_c} = \frac{4}{5}$$

60 The value of R_2 and R_3 should be high with respect to R_1 and thereby the "load" on the tube 5 due to the shunting effect of the resistors can be made negligible. As a matter of fact, more so than in the conventional capacity coupled amplifiers.

65 Referring to Figs. 3 and 4, the amplifier circuit shown comprises three cascaded stages utilizing preferably high mu triodes in the first two stages and a suitable output tube which may be a pentode. In all figures, the heater circuit for the tubes has been omitted for the sake of simplicity, for depending upon the type of operation desired, the filaments may be energized by either alternating or direct current. The power supply 70 shown is the commonly used full wave rectifier

type circuit for the anode potential side of the system and a half-wave rectifier furnishes the negative side of the supply. It is to be understood that other types of supplies may be used, or batteries, as long as the filtering is satisfactory for obtaining pure direct current and the regulation of the supply adequate for high gain circuits, as shown in Figs. 1 or 2.

The three-stage amplifier shown in Figs. 3 and 4 illustrates the adaptability of the basic circuit previously described to the cascading of several stages and to energization from power line operated supplies. Essentially the circuit is similar as to basic details to the one shown in Fig. 1 and the modification illustrated in Fig. 4 includes the inverse feed-back connection in the manner similar as shown in Fig. 2. In both figures the additional voltage amplifying stage has identical component elements which are marked with the same reference characters as used in the preceding stage, except primary indices are affixed for the purpose of identification of the additional stage. Other stages may be inserted in the same manner within practical limitations governed by the gain obtained and the type of vacuum tubes chosen. The explanation previously given regarding the operation of the system applies also to the circuits shown in these figures.

Additional elements in Figs. 3 and 4 include the power supply for the anode and grid potentials comprising the supply transformer 34, the primary winding 35 which is to be energized from a suitable alternating-current power line. The secondary winding 37 connects to the anodes 38 and 38' of the rectifier tube 39. The center tap of the secondary winding is connected to the conductor 22 which forms the neutral point between the two supply voltages.

The extreme positive side of the supply includes a suitable filter choke 40 and the conventional filter condensers 41 and 42 between the return of the winding 37 and the cathode 43 of tube 39 to which one terminal of the filter choke 40 is connected. The extreme negative side of the supply is obtained by the half-wave rectifier tube 44, the cathode 45 of which is connected to one terminal of the secondary winding 37, and the anode 47 thereof in series with filter resistor 48 to the supply conductor 9. Filter condensers 50 and 51 connect to the respective terminals of the filter resistor 48 and the supply line 22. The negative portion of the supply between conductors 22 and 9 is also paralleled by voltage regulator tubes 52 and 53 connected in series.

The output tube 19 utilized in this arrangement is of the pentode type having its suppressor grid 24 connected to the cathode 21, whereas the screen grid 27 is connected to the positive side through a suitable resistor 33 which is also connected to the neutral conductor 22 through a voltage regulator tube 36, in order that the potential of the screen grid 27 should be maintained uniform. Additional voltage regulation between the amplifying stages may be obtained by voltage regulator tubes 46 and 49 and series resistors 54 and 53 between the supply conductor 15 and the load resistors 14 and 14'. The type of voltage regulator tubes particularly suitable in this connection may be the neon or similar inert gas

filled discharge devices generally used in the radio art.

The circuit of Fig. 4, as stated before, is identical with the one in Fig. 3, except for the inverse feed-back circuit which comprises a common connection between cathodes 7 and 21 of tubes 5 and 19 respectively, and variable resistor 31 in series between the cathode 21 and the supply conductor 22. The voltage drop across resistor 31 depends upon the plate current variations of tube 19 and the amount of the drop may be regulated by the rider 13 of the resistor 31. The voltage obtained will tend to increase the potential of the cathode 7 to a value more positive with respect to conductor 22, thereby increasing the negative bias on the grid 3 of vacuum tube 5, tending to reduce amplification. The fact that all cathodes are at equipotential makes the application of inverse feedback very simple in this amplifier. In this figure an output transformer 32 takes the place of the relay winding 26, merely by way of example, illustrating the adaptability of the system to A. C. voltage amplification.

In a practical embodiment of the circuit shown in Fig. 3, the following values of component elements were found to give good performance.

Potentiometer 1=500,000 ohms

Potentiometer 6=20,000 ohms

Resistors 14=500,000 ohms

Resistors 16=2,500,000 ohms

Resistors 17=1,500,000 ohms

Resistors 18=1,000,000 ohms

Voltage regulator tubes type VR 150-30

Anode supply voltage=150

Bias supply voltage=300

Power supply voltage=400

Tubes used were, RCA types

#5=6C8G

40 #51=6C8G

#19=6C6

#39=80

#44=6X5

What is claimed is:

45 An amplifier comprising a first tube containing an anode, a cathode and a control electrode, a voltage source having one of its terminals connected to said anode through a first impedance, a connection between the cathode of said first tube and an intermediate voltage-point on said voltage source, an impedance shunted between the anode of said first tube and the opposite terminal of said voltage source, a second tube comprising an anode, a cathode and a control electrode, a connection between the last-mentioned control electrode and an intermediate point on the last-mentioned impedance, a load connected between the anode of said second tube and the first-mentioned terminal of said voltage source, an impedance connected between the cathode of said second tube and the first-mentioned intermediate voltage-point, an impedance connected between an intermediate point of the last-mentioned impedance and said other terminal of said voltage source, and a connection between an intermediate point of the last-mentioned impedance and the control electrode of said first tube.

WILSON M. BRUBAKER.
